ADJUSTABLE MUZZLE CHOKE

Richard M. Cutts, The Plains, Va.

Application March 2, 1955, Serial No. 491,625

5 Claims. (Cl. 42—79)

This invention relates to adjustable muzzle chokes and more particularly to such chokes which are intended primarily for use with shotguns to provide uniform and adjustable shot patterns.

Heretofore various adjustable choke devices have been suggested and used with shotguns and have enjoyed wide commercial acceptance. These prior art devices, however, include various undesirable features which are overcome in the novel adjustable choke device of the present invention. For example, in certain prior art adjustable choke devices inadequate support is provided along the length of the yielding segments which when bent from the cylindrical to the conical provide for the choking action and the segments are therefore non-uniformly distorted and vibrate upon firing resulting in non-uniform shot patterns and irregular choking action. In other devices where more than one turn of the choke adjusting sleeve is required from open to full choke it is impossible to determine the amount of choke unless the sleeve is moved to one extreme or the other and then adjusted to the desired choke. In other prior art devices the arrangement of parts is such that excessive friction exists between the adjusting sleeve and the segments and it is manually difficult to adjust the choke to the desired degree. In other devices the arrangements of the elements thereof are such that they are readily affected by weather conditions or the presence of dirt or burnt powder so that frequent cleanings and dismantlings of the device are required for accurate operation thereof.

All of these objections are overcome by the novel choke devices of the present invention and other advantages are inherent therein as will more fully appear hereinafter.

It is therefore an object of the present invention to provide novel adjustable muzzle chokes in which the segments are uniformly supported throughout their lengths to prevent undesirable or unusual distortions thereof and to provide a uniform contraction for any choke position.

Another object is to provide such a choke in which the segments are constantly flexed along their length in a uniform contraction and are supported against vibration.

Another object is to provide such a choke having a micrometer adjustment so that the same point on the micrometer scale is always reached for the same number of turns of the choke adjusting sleeve.

Another object is to provide such a choke in which the supports for the segments are line supports which change position with each change of curve of the segments and for each degree of choke utilized.

Another object is to provide such a choke in which the segments are of constant thickness at the positions of minimum thickness thereof to insure uniform flexing of the segments.

Another object is to provide such chokes in which the ability of the segments to flex along their full length compensates for any minor errors occurring in the manufacture of the device to provide uniform adjustable choking.

Another object is to provide such chokes having a mini-

mum of friction between the moving parts to insure ease and rapidity of choke adjustment.

Another object is to provide such chokes in which there is a positive lock of the choke adjusting sleeve at fully open and at fully choked positions.

Another and still further object of the present invention is to provide such chokes which will provide longer service without cleaning because of the clearances provided between the moving elements thereof.

Other and still further objects of the present invention will appear from the following description of illustrative embodiments of the same as will appear more fully hereinafter.

The novel adjustable muzzle chokes of the present invention are capable of various mechanical embodiments a number of which are shown in the accompanying drawings and are described hereinafter to illustrate the same. These illustrative embodiments of the present invention should in no way be construed as defining or limiting the same and reference should therefore be had to the appended claims to determine the scope of this invention.

In the accompanying drawings in which like reference characters indicate like parts,

Fig. 1 is a view, partly in section, of the forwardly extending shell of one embodiment of the present invention showing the shell threaded for engagement in a spacing device, not shown, and showing the position of the micrometer readings and the arrangement of the segments;

Fig. 2 is a view of the shell of Fig. 1 seen from the right thereof;

Fig. 3 is a view partly in section of a suitable choke adjusting sleeve for use with the shell of Fig. 1 showing the conically tapered inner surface of the sleeve tapered in a curve of continuously increasing slope forwardly and inwardly toward the muzzle end thereof;

Fig. 4 is an end view of the sleeve of Fig. 1 as seen from the right thereof;

Fig. 5 is an axial sectional view of the shell of Fig. 1 and the sleeve of Fig. 3 in assembled position with the locking ring in position to provide positive locking of the sleeve in open and in fully choked position;

Fig. 6 is a partial axial sectional view of another embodiment of the choke device of the present invention in assembled condition showing the segments supported by ball bearings;

Fig. 7 is a partial axial sectional view of another embodiment of the present invention in which the segments are supported by split rings;

Fig. 8 is an axial view partly in section of another embodiment of the present invention in which the segments are supported by a continuous helix formed on the outer surfaces thereof and interrupted in the way of the slots between the segments;

Fig. 9 is an axial view partly in section of a modification of the embodiment of Fig. 1 and in which the choke device is designed for mounting on the end of a shotgun barrel not employing a recoil absorbing or compensating device; and

Fig. 10 is an enlarged diagrammatic showing of the embodiment of Fig. 9 to illustrate a method of obtaining the curve of the interior surface of the choke adjusting sleeve showing dimensions suitable for a choke device for use with a twelve gauge shotgun employing a spacing device.

Referring now to the drawings, and more particularly to Figs. 1 through 5, a shell 10 is provided which is externally threaded at 9 for engagement in the internally threaded muzzle end of a recoil compensating device of known construction which is therefore not here illustrated. Shell 10 is provided with an internal bore 11 which forms a continuation of the bore of the shotgun and bore 11 is flared as at 12 to the larger internal diameter of the recoil compensating device. The forward end of shell

10 is formed into a plurality of forwardly extending relatively resilient segments 13 by slots 14 which extend parallel to the axis of shell 10 from the forward end thereof to adjacent the shoulder 15. Any suitable number of slots 14 may be employed to provide any suitable number of segments 13 and as here shown there are six such slots 14 and six such segments 13.

A plurality of uniformly spaced parallel lands or raised contact surfaces 16, separated by suitable grooves 17 are formed circumferentially around the segments 13 at right angles to the axis of shell 10 and are interrupted in way of slots 14. Grooves 17 may terminate at their bottoms in the same cylindrical surface so that the thickness of segments 14 is uniform beneath all of the grooves 17 as shown at 18. The upper peripheral surfaces of lands 16 are rounded in cross section as shown at 19 and the heights of lands 16 decrease progressively toward the muzzle of shell 10 so that parallel tangents to the curved surfaces 19 will lie in a curve of the type generally shown in Fig. 10.

A groove 20 is provided between shoulder 15 and the adjacent land 16 to receive the locking device, as will more fully appear hereinafter, and shell 10 is threaded at 21 to receive a choke adjusting sleeve to be described with respect to Fig. 3. Shell 10 is provided between threads 9 and threads 21 with a cylindrical surface 22 upon which suitable micrometer readings 23 may be engraved to show suitable principal and intermediate choke positions.

Choke adjusting sleeve 24 is shown in Fig. 3. Sleeve 24 is internally threaded at 25 for engagement with threads 21 of shell 10 and is provided with a hollow cylindrical extension 26 which surrounds surface 22 when the choke device is in assembled condition providing a shield and a circumferential end 27 which cooperate with the micrometer readings 23 to indicate the degree of choke of the device. Sleeve 24 is circumferentially grooved at 28 to receive a split locking ring 29. Locking ring 29 is provided with an inwardly turned extension 30 which passes through hole 31 in sleeve 24 for movement in groove 20 of shell 10. Sleeve 24 is provided with a tapered conical inner surface 32 curved as above described.

The outer surface of sleeve 24 may be suitably knurled as to 33 to facilitate rotation of the sleeve.

In assembling the choke device of Figs. 1-5 sleeve 24 is inserted over segments 13 and around the several lands 16 until threads 25 engage threads 21. Rotation of sleeve 24 in a clockwise direction as seen in Fig. 4 then engages threads 25 and 21. Thereafter snap ring 29 is mounted in groove 28 with extension 30 extending through opening 31 and into groove 20 of shell 10. Extension 30 abuts the adjacent land 16 when the choke device is in fully open position to prevent accidental removal or loss of sleeve 24 and abuts surface 15 of shell 10 when the choke device is in fully choked position thus providing a positive lock for the sleeve 24 in both extreme positions of choke.

Since the outer surfaces of lands 16 are rounded in cross section, as described above, it is apparent that the contact of each land with tapered conical surface 32 of sleeve 24 will be a circumferential line contact providing reduced friction when sleeve 24 is rotated. It is also apparent that as sleeve 24 is rotated the circumferential line contact for each land 16 will change in position around the curve surface of the land but that a uniform force will always be exerted on the land which in turn is imparted to the segments 13. Since grooves 17 terminate in the same cylindrical surface and are of uniform thickness beneath all of the grooves 17 as at 18 the segments 13 will be uniformly flexed and uniformly supported throughout their entire length thus preventing vibration of the segments 13 or undesired distortions thereof.

The embodiment of Fig. 6 differs from that of Figs. 1-5 in that the lands 16 are not employed and in place thereof ball bearings in snap-ring type races are used to

support the segments 13. As shown in Fig. 6, shell 10 is provided with an annular land 34 to act as a stop for extension 30 of snap ring 29. Land 34 does not engage surface 32 of sleeve 24. Shell 10 is provided with a plurality of spaced circumferentially extending grooves 35 in which suitable snap-ring type races 36 are mounted to receive the ball bearings 37. Races 36 do not completely surround segments 13 and are spaced apart at their ends as shown at 38 to allow for contraction when sleeve 24 is rotated toward fully choked position.

Grooves 35 end in the same cylindrical surface so that the thickness of segments 13 may be uniform beneath the grooves 35 to insure uniform flexing of the segments. Races 36 and ball bearings 37 are chosen for size and diameter, respectively, so that the points of contact of the several ball bearings 37 lie on surface 32 of sleeve 24.

In the embodiment of Fig. 6 the muzzle ends of segments 13 are rounded as at 38 to form a circumferential line contact with surface 32. Here again it is obvious that the segments 13 are provided with uniform support throughout their lengths; are prevented from vibration; are prevented from undesirable distortion; that friction between the moving elements is reduced to a minimum; and that clearances are provided which allow long service of the device without cleaning.

The embodiment of Fig. 7 employs snap rings in place of the snap-ring type ball bearing races of Fig. 6. In this embodiment shell 10 is provided with a plurality of circumferential grooves 39 spaced apart and extending around the segments 13 and snap rings 40 are mounted in grooves 39. Snap rings 40 are spaced apart at their ends, as shown at 41, to allow for contraction of the rings when sleeve 24 is rotated toward choked position. Rings 40 are circular in cross section and are graded in size from larger to smaller as the muzzle end of shell 10 is approached so that each ring is in circumferential line contact with surface 32 of sleeve 24. As surface 32 moves inwardly or outwardly to vary the choke it is obvious that the circumferential lines of contact will shift but that a uniform support will always be provided for segments 13 which prevents vibration and undesired distortion. Here again, the muzzle ends of segments 13 are rounded, as at 38, to provide a circumferential line contact with surface 32 so that segments 13 are uniformly supported throughout their lengths by circumferential line contacts acting to reduce friction at surface 32.

The embodiment of Fig. 8 differs from those described above in that a continuous helix 42 of diminishing height toward the muzzle end of shell 10 surrounds segments 13 and is interrupted in way of slots 14 to permit flexing of segments 13. The tops of the turns of helix 42 are rounded in cross section as shown at 43 so that a helical line of contact is had with surface 32 of sleeve 24. The thickness of segments 13 between the turns of helix 42 is constant so that segments 13 will be uniformly flexed by the action of sleeve 24. The turns of helix 42 grade downwardly in height from the rearmost turn to the turn adjacent the muzzle end of shell 10 and are graded in height in accordance with curve 32 so as to continuously engage the same in a helical line of contact. The turns of helix 42 are spaced to provide sufficient clearance so that frequent take down and cleaning of the device is not required.

In the embodiment of Fig. 8 the segments 13 are provided with a uniform support along their length and are flexed uniformly by the action of surface 32 of sleeve 24 to prevent vibration of segments 13 or undesired distortions thereof. In this embodiment, as in those of Figs. 6 and 7, the muzzle ends of segments 13 are rounded as at 38 to provide a circumferential line contact with surface 32 adjacent the muzzle end of shell 10. It is obvious that in this embodiment the line of contact with surface 32 will change with the position of sleeve 24 without changing the uniform support of segments 13. Friction is reduced to a minimum. A positive lock at

fully opened and fully choked positions is provided by extension 30 of snap ring 29 and micrometer readings are obtained between circumferential edge 27 and scale 23.

The embodiment of Fig. 9 is designed for direct mounting on the barrel of a shotgun. With this embodiment barrel 44 is provided with an internal bore 45 and is externally threaded at 46 adjacent its muzzle end to receive internal threads 47 of shell 10. It is obvious that other means may be employed for securing shell 10 to barrel 44 and such means may include shrinking shell 10 upon shell 44, silver soldering shell 10 on barrel 44 and the like.

Shell 10 is provided with internal bore 11 which is a continuation of bore 45 and is also provided with an annular surface 22 upon which ring 48 is suitably secured as at 49 by welding, silver soldering, shrinking, pinning or the like. Ring 48 covers a part of threads 21 which receive internal threads 25 of sleeve 24. Sleeve 24 is circumferentially grooved at 31 to receive split ring 29 and extension 30 thereof passes through sleeve 24 and moves in grooves 20 to abut shoulder 15 in fully choked position and to abut the adjacent circumferential land 16 in fully opened position. In this embodiment micrometer readings 23 are engraved in surface 50 of sleeve 24 and cooperate with the circumferential edge 51 of ring 48 to show the choke setting of the device.

Fewer and shallower lands 16 are used in the embodiment of Fig. 9 and the lands 16 are more widely separated. Here again the thickness of segments 13 is uniform beneath grooves 17 so that segments 13 will be uniformly flexed by the action of sleeve 24. The muzzle ends of segments 13 are rounded as at 38 to provide a circumferential line contact with surface 32 of sleeve 24 and the height of lands 16, which are rounded in cross section to provide circumferential line contacts with surface 32, are selected in accordance with the shape of surface 32 so that uniform support is provided at all times throughout the length of segments 13. Lands 16 are, of course, interrupted in way of slots 14, as is seen at 52, to allow flexing of segments 13.

The embodiment of Fig. 9 of the present invention provides the desired uniform flexing of segments 13 with uniform support of segments 13 throughout their length to prevent vibration and undesired distortion thereof while at the same time reducing friction between the moving parts with clearance therebetween sufficient to permit long use of the device without disassembly for cleaning. The micrometer reading is accurate and exact and the moving parts are provided with maximum protection against the entry of dirt.

Fig. 10, which is enlarged, and not to scale, shows suitable dimensions for the embodiment of Fig. 9 for an adjustable muzzle choke for a twelve gauge shotgun. The dimensions are in inches and from such dimensions the shape of curve surface 32 can be readily determined. The shape of curve 32 is determined in part by the number of turns of sleeve 24 which are desired to flex segments 13 from fully opened position to fully choked position. The internal diameter at the muzzle of segments 13 for a twelve gauge shotgun at fully open position may be .750 inch based upon the longitudinal length from the muzzle of the shotgun. All of these figures are variable and are based on the dimensions of the Cutts Compensator which are well known. This diameter is .725 inch for modified choke and .705 inch for full choke. Thus the difference of the diameter between fully open and fully choked positions is .045 inch and if three turns are employed to effect this choke then the diameter at the muzzle must be reduced .015 inch for each turn of sleeve 24. If threads 21 and 25 are twenty turns to the inch then the distance which surface 32 moves longitudinally for one turn of sleeve 24 is .05 inch. The pitch of curve 32 extending away from the line of contact of surface 38 at fully opened position is therefore .015 inch on .05 inch. Similar calculations for each of the cir-

cumferential line contacts for each land 16 can be calculated in similar manner and the shape of curve surface 32 thereby determined.

It will now be apparent to those skilled in the art that by the present invention I have provided an adjustable muzzle choke which in every way satisfies the several objectives discussed above.

Changes in or modifications to the illustrative embodiments of my invention may now be suggested without departing from the present inventive concept. For example, the internal curve surface described above for sleeve 24 may be transposed to the outer surfaces of segments 13 and the various lands, ball bearing races, split rings, and helix, as described above, transferred to the inner surface of sleeve 24. Further, if non-uniform flexing is desired for segments 13 at any given point the thickness may be reduced at that point, as by annular grooving, to provide the desired flexing. It is to be emphasized, however, that I prefer a uniform thickness of segments 13, as described above, to give a uniform flex throughout their length. In view of the above, reference should therefore be had to the appended claims to determine the scope of this invention.

What is claimed is:

1. In an adjustable muzzle choke for shotguns having a plurality of resilient axially extending circumferentially disposed segments and a sleeve longitudinally movable over said segments, means for flexing and uniformly supporting said segments along their length including an internal surface in said sleeve tapered in a curve of continuously increasing slope forwardly and inwardly toward the muzzle end thereof and a plurality of circumferentially disposed spaced substantially parallel raised contact surfaces on said segments of progressively decreasing heights toward the muzzle end of said segments, said segments having uniform thickness between said raised contact surfaces, said raised contact surfaces having their surfaces of contact rounded in cross section and engaging said internal surface in circumferential lines of contact which change position with each change of curve of the segments and for each degree of choke utilized.

2. A muzzle choke as described in claim 1 in which the muzzle ends of said segments have outer surfaces rounded in cross section and engaging said internal surface in a circumferential line of contact which changes position with each change of curve of the segments and for each degree of choke utilized.

3. In an adjustable muzzle choke for shotguns having a plurality of resilient axially extending circumferentially disposed segments and a sleeve longitudinally movable over said segments, means for flexing and uniformly supporting said segments along their length including an internal surface in said sleeve tapered in a curve of continuously increasing slope forwardly and inwardly toward the muzzle end thereof and a plurality of circumferentially disposed spaced substantially parallel raised contact surfaces on said segments interrupted between said segments and of progressively decreasing heights toward the muzzle end of said segments, said segments having uniform thickness between said raised contact surfaces, said raised contact surfaces having their surfaces of contact rounded in cross section and engaging said internal surfaces in circumferential lines of contact which change position with each change of curve of the segments and for each degree of choke utilized.

4. In an adjustable muzzle choke for shotguns having a plurality of resilient axially extending circumferentially disposed segments and a sleeve longitudinally movable over said segments, means for flexing and uniformly supporting said segments along their length including an internal surface in said sleeve tapering in a curve of continuously increasing slope forwardly and inwardly toward the muzzle end thereof and a plurality of circumferentially disposed spaced parallel lands on

said segments interrupted between said segments and of progressively decreasing heights toward the muzzle end of said segments, said segments having uniform thickness between said lands, said lands having outer surfaces rounded in cross section and engaging said internal surface in circumferential lines of contact which change position with each change of curve of the segments and for each degree of choke utilized.

5. A muzzle choke as described in claim 4 in which the muzzle ends of said segments have outer surfaces rounded in cross section and engaging said internal surface in a circumferential line of contact which changes

position with each change of curve of the segment and for each degree of choke utilized.
